CHARLES ALFRED MILLS, OF SHEFFIELD, ENGLAND, ASSIGNOR TO DAVY BROTHERS, LIMITED, OF SHEFFIELD, ENGLAND.

HYDRAULIC VALVE.

1,293,858.

Specification of Letters Patent. Patented Feb. 11, 1919.

Application filed August 2, 1918. Serial No. 248,082.

To all whom it may concern:

Be it known that I, CHARLES ALFRED MILLS, a subject of the King of Great Britain, residing at Sheffield, Yorks, England, 5 have invented new and useful Improvements in Hydraulic Valves, of which the following is a specification.

Hydraulic piston-valves of the well-known type wherein the piston or spindle carries 10 a leather packing-ring for the purpose of controlling a port in the valve-casing, have hitherto suffered from a serious disadvantage owing to the fact that the leather, in 15 passing over the annular or virtually annular valve-port in the surrounding valve-casing, is apt to spread out radially under the hydraulic pressure to which it is exposed, with the result that the leather, becoming wedged into the port, is in time shorn away 20 and the packing is thus rendered useless. The object of the present invention is to overcome this difficulty by providing a construction such that the leather will remain completely inclosed on its outer as well as 25 on its inner surface at all points in its travel, and will thus be prevented from spreading and becoming wedged into the valve-port when passing over the latter.

For this purpose, each leather packing- 30 ring to which the invention is applied is provided with an inwardly-cylindrical movable shield for the reception of the packing-ring during such portion of its travel as extends across the port-opening; the shield, which 35 has the same internal diameter as that section of the bore of the valve-casing wherein the packing-ring normally rests, being caused to move as one with the packing-ring only so long as the latter remains completely 40 housed within it, and being at other times retained by yielding pressure in position to constitute in effect a continuation of said section of the bore in the valve-casing.

In a practical embodiment of the invention 45 the shield is movable, lengthwise of the valve-spindle, within a cavity or chamber surrounding the spindle at the side of the port remote from that section of the bore wherein the packing-ring normally rests; 50 the shield, when the port is closed and the leather housed in the bore of the valve-casing, being held by spring-pressure in or across the port, while the spindle and shield are adapted to so engage one another when 55 (during the port-opening movement) the

leather has passed from the bore of the valve-casing entirely within the shield, that the continued movement of the spindle will cause the shield (with the leather inclosed within it) to be carried past the now open 60 port in opposition to the spring-pressure whereby, on the return or port-closing movement, the shield is caused to resume its position in or across the port before the continued movement of the spindle carries the 65 leather out of the shield and into the bore of the valve-casing.

The accompanying drawing, which illustrates one form of valve to which the invention is applied, shows in axial section a 70 pair of single-acting piston-valves (for a hydraulic press or similar hydraulic apparatus) in each of which the leather packing-ring carried by the valve-spindle is provided with a movable shield. 75

The two piston-valves, whereof that on the left of the drawing is the inlet valve and that on the right the exhaust valve, are arranged side-by-side with their axes vertical, within a single casing having a central chamber *a* through which both valve-spindles pass and which is in open communication with a lateral branch *b* connected with the press cylinder (not shown). Above the chamber *a* is a port *c* surrounding the 80 inlet valve spindle and in open communication with a second lateral branch *d* connected with the source (not shown) of hydraulic pressure; this inlet port *c* being adapted to be put in communication with the chamber *a* by way of a vertical bore *c'* through which passes the inlet valve spindle. Beneath the chamber *a* is a passage *e* in open communication with a third lateral 85 branch (not shown) connected with the exhaust; this exhaust passage *e* being adapted to be put in communication, by way of a vertical bore *f* through which passes the exhaust valve spindle, with that portion *f* of the central chamber *a* which immediately 90 surrounds said spindle and which thus constitutes in effect the exhaust valve port. 95

The two valves are similar in construction, and hence the same description applies equally to either valve, it being understood 100 that the opening of the respective valves alternatively is effected by means of a cam *g* on a shaft *g'* which can be rocked in either direction at will from a mid angular position so as, while leaving one of the valves resting 110

in the lowered or closed position, to open the other valve by raising its tappet h' and spindle h against the pressure of a spring j in the well-known manner. In the drawing, 6 the left-hand or inlet valve is shown as closed while the shaft g' and cam g have been rocked so as to open the right-hand or exhaust valve.

The sliding leather k in each valve is of 10 the usual U-shape in cross section, and is held in position against an upwardly presented shoulder l on the valve-spindle h by a gland-ring m at the lower end of a sleeve m' , which, fitting over the spindle, is forced 15 toward the shoulder l by means of a cap n which is screwed at n' over the upper end of the spindle so as to be adapted to receive, and transmit to the spindle h , the thrust of the valve-closing spring j . The external diameter of each leather k is adapted to fit that section c' or f' of the bore wherein the leather rests when the valve is closed as shown in the case of the inlet valve, but out of which the leather is raised entirely when 20 the valve is opened as shown in the case of the exhaust valve; the lips of the U-shaped leather being directed upward in each case so that the leather will be distended radially by hydraulic pressure when the valve is 25 closed. The shoulder l on the valve-spindle may fit the bore-section at c' or f' as indicated, but immediately beneath the shoulder the spindle has a portion l' of reduced diameter so that, when the leather k and shoulder l are raised out of the bore, the latter will be open to the port c or f as shown in 30 the case of the exhaust valve.

Each sliding leather k is provided with a 40 movable annular shield o , inwardly cylindrical, which throughout the greater part of its length has the same internal diameter as the bore-section c' or f' and which extends upward across the port c or f into a chamber o' surrounding the sleeve m ; this shield o having at its upper end an internal flange p which fits slidably over a portion of the sleeve m' having a diameter less than the diameter of the bore c' or f' . Normally (i. e. so long as the valve is closed) the shield o is 45 held down by a spring r so that its flat annular lower end rests in contact with the level surface surrounding the upper orifice of the bore-section c' or f' , the shield o then constituting virtually an upward continuation 50 of said bore-section; but when the spindle h has been raised sufficiently to carry the leather k upward wholly within the shield o , a shoulder s at the lower end of the sleeve m' engages the internal flange p on the shield 55 and causes the latter, during the remainder of the upward movement of the spindle h , to rise as one with the spindle and leather, thus opening the port c or f to the bore-section c' or f' . On the valve-spindle h being allowed 60 to descend under the stress of the spring j , 65

the shield o is carried downward by the spring r until it comes to rest against the surface surrounding the upper orifice of the bore-section c' or f' after which the spindle h in its further descent to normal position 70 carries along with it the leather k which thus passes from within the shield o into the bore-section c' or f' .

It will be noticed that, in the example illustrated, the leather k rests normally (i. e. 75 so long as the valve remains closed) partly in the bore-section c' or f' and partly within the shield o , into which the lips of the leather are shown as then extending; but it is obvious that the leather might normally rest wholly within the bore-section c' or f' with its lips either at or below the level of the upper orifice of the bore. The arrangement shown in the drawing, however, eliminates any possibility of the lips of the leather 80 failing to enter the shield accurately and smoothly during the upward movement of the valve-spindle, while the same time the length of upward travel given to the valve-spindle can be made less than would otherwise be necessary.

The leather k is distended by hydraulic pressure which may be allowed to gain access to its inner surface by way of notches on the outer periphery of the shoulder s on the sleeve m' and corresponding notches on the inner periphery of the flange p on the sleeve o , or by other suitable channels. The shield-spring r is shown as taking its abutment against the lower end of a gland t which closes the upper end of the chamber o' and serves to hold in position a stationary U-shaped packing-leather t' through which the cap n slides at the level where this cap passes within the fixed cover j' forming an abutment for the valve-closing spring j . The lower end of the valve-spindle h is packed by a stationary U-shaped leather v .

It will be seen that the shield o has a to-and-fro movement of less extent than that of the valve-spindle h and leather k , and that, during the port-opening movement, the leather k cannot emerge from the bore-section c' or f' without having entered the shield; and that conversely, during the post-closing movement, the leather k cannot emerge from the shield o without simultaneously entering the bore-section c' or f' . Hence at no point in its travel is the leather k unsupported both externally and internally, and consequently the hydraulic pressure, gaining access to the interior of the leather, cannot distend the latter beyond a diameter equal to that of the bore-section c' or f' .

In some cases, more particularly where the valve-spindle works vertically and performs its port-closing movement in the downward direction, the shield-spring may be dispensed with, the frictional contact of the leather 125 130

- within the shield sufficing to insure the return of the latter to its seated position in or across the port. In this case the provision of a vent-hole or holes in *e. g.* the inwardly-5 flanged upper end of the shield will insure the shield as a whole remaining in hydraulic equilibrium and devoid of any tendency to leave its seated position so long as the port is closed.
10. What I claim is:—
1. In a hydraulic piston-valve of the type referred to, the combination with a leather packing-ring carried by the valve-spindle for the purpose of controlling a port in the 15 valve-casing, of an inwardly-cylindrical movable shield for the reception of said packing-ring during such portion of its travel as extends across the port-opening; the shield having the same internal diameter 20 as that section of the bore of the valve casing wherein the packing ring normally rests, means for causing the shield to move as one with the packing ring only so long as the latter remains completely housed within
  - it, and means for causing it at other times to 25 be retained by yielding pressure in position to constitute in effect a continuation of said section of the bore in the valve casing.
  2. In a hydraulic piston-valve of the type referred to, the combination of a valve cas- 30 ing having a port and provided with a chamber and a bore in axial registry and located upon opposite sides of said port, a valve spindle movable lengthwise of said chamber and port, a packing-ring carried by 35 said spindle for controlling said port and normally resting in said bore, an inwardly-cylindrical shield for the reception of said packing-ring during such portion of its travel as extends across the port, said shield 40 being movable within said chamber, a spring for normally holding the shield in registry with the port, and coöperating means on said shield and valve-spindle adapted to engage each other whereby said shield and 45 spindle are concurrently moved during part of the movement of the latter.

CHARLES ALFRED MILLS.
